United States Patent

Des. 236,926
Patented Sept. 30, 1975

236,926

TABLE

Thomas A. Alexander, Santa Monica, Calif., assignor to
Zapata Designs, Inc.

Filed Jan. 25, 1974, Ser. No. 436,439

Term of patent 14 years

Int. Cl. D6—03

U.S. Cl. D6—177

Fig. 1

Fig. 2

Fig. 3

Fig. 4

Fig. 5

Fig. 6

FIG. 1 is a perspective view of a table embodying my new design illustrating the top, front and left side of the table.

FIG. 2 is a view of the table illustrating the top of the table.

FIG. 3 is a view of the table illustrating the right side of the table.

FIG. 4 is a view of the table illustrating the left side of the table.

FIG. 5 is a view of the table illustrating the front of the table.

FIG. 6 is a view of the table illustrating the bottom of the table.

I claim:

The ornamental design for a table, substantially as shown and described.
